COMBINED SOFA SEAT AND BED

Harry Neck, Los Angeles, Calif.

Application August 31, 1956, Serial No. 607,482

7 Claims. (Cl. 5—46)

This invention relates to articles of furniture of the type commonly termed "sofa beds" and which may be readily converted into a sofa seat or into a bed.

Sofa beds of many different types have heretofore been made but many of them have the objection that it involves too much difficulty and work to change from a sofa to a bed and vice versa. It is consequently one of the objects of this invention to provide a sofa bed of this type with an improved mechanism connecting the several parts so that the change from a sofa to a bed and vice versa can be easily made.

It is also an object of this invention to provide a sofa bed which is so constructed that the parts of the mechanism are releasably locked in position to form a sofa and will not move out of their bed positions except by application of a small force thereto. Another object is to provide a soft bed in which the main frame or support is so mounted that it can easily be tipped upwardly when the parts are in the bed position to permit sweeping the floor underneath the same.

It is also an object of this invention to provide springs or other resilient means which serve to counteract the weight of a part of the sofa when it is swung upwardly partly into bed position and then to resiliently oppose further movement in a downward direction into bed position, so as to avoid possible injury to a person operating the sofa bed.

Other objects and advantages will be apparent from the following description of one embodiment of the invention and the novel features will be particularly pointed out hereinafter in connection with the appended claims.

In the accompanying drawings, which illustrate by way of example, one embodiment of this invention and in which none of the padding for the sofa seat nor the bed mattress is shown:

Fig. 1 is a side elevation of the sofa bed when the parts thereof are arranged and locked in position to form a sofa seat.

Fig. 2 is a similar view showing some of the parts of the sofa moved partly into position to form a bed.

Fig. 3 is a side elevation, partly in longitudinal section, showing the parts in their positions to form a bed.

Fig. 4 is a partial fragmentary top plan view thereof on an enlarged scale, approximately on line 4—4 Fig. 3.

Fig. 5 is a continuation of Fig. 4, approximately on line 5—5 Fig. 3.

Fig. 6 is a fragmentary plan view thereof on line 6—6 Fig. 2.

Figs. 7 and 8 are sectional fragmentary elevations respectively on lines 7—7 and 8—8 of Fig. 4.

Fig. 9 is a side elevation thereof showing the frame tipped up for sweeping underneath same.

Fig. 10 is a sectional side elevation thereof showing power means for moving the parts from the sofa to the bed position and vice versa.

The main frame or support of the device includes upright posts 10 and 11 which form parts of a pair of end members 15 which may also form arm rests for the

2

opposite ends of the sofa. These end members are connected by means of a rear cross member 17, a front cross member 18, and a lower cross member 19. 16 represents triangular pieces at the back corners of the support or frame which reinforce the same. The frame may be supported on feet or legs in the usual manner.

20 represents the frame of the back of the sofa which may be provided with any suitable upholstery (not shown) and which when the parts are moved into bed position 10 constitutes an end of the bed. The bed frame, in addition to the end section which also forms the back rest of the sofa, includes three sections which have the usual springs upon which a mattress rests. These sections fit into the support and under the seat portion of the sofa when the parts are in the sofa position. This back member 20 is of hollow construction, and a flat bar or strap 21 is rigidly bolted or otherwise secured thereto at each end of the back member. In the drawings the linkage is shown for only one side of the bed, it being understood that the linkage on the opposite side thereof is a duplicate of that shown.

The bar 21 is pivotally connected at its lower end at 13 with one end of a link 22, the other end thereof being connected to an end of a coil spring 24. The other end 25 of the coil spring is connected to a fastening member 25 fixed on the frame of the sofa bed.

27 represents a bed leg member which extends substantially parallel to the base of the sofa back 20 and which forms a foot or supporting leg for the linkage remote from the support when in bed positions. This leg member 27 is suitably secured to the bar 21 in the construction shown. The bar 21 has an offset or U-shaped portion 23 which extends into proximity to the leg 27 and is welded thereto, as shown in Fig. 5. The leg 27 has a locking latch or dog 28 pivoted thereon at 29. This pivot 29 is located at one side of the latch 28 so that this latch will tend to swing by gravity about the pivot to the left as shown in Figs. 1 and 2. The other end of this latch has an inclined or beveled end 30 and a notch 31.

40 When the parts are in their sofa positions as shown in Fig. 1, the locking latch 28 will swing by gravity to the left and engage with a fixed holding part 33 secured to cross member 34 of the frame or support of the sofa bed. Consequently when in this position, the back 20 of the latch 28, however, may be released when desired, and for this purpose the latch is provided with an upwardly extending part 36 to which a strap or latch actuating member 37 is secured. Consequently when the strap or actuating member 37 is pulled the latch will be swung

45 about its pivot out of engagement with its holding part 33 so that the sofa back 20 may then be swung upwardly by means of said strap into the position shown in Fig. 2. The leg member 27 is also connected by means of

50 pivots 38 and 39 with two links or frame members 40 and 41 respectively, the pivots being at opposite sides of the strap 21. The other ends of the frame members 40 and 41 are pivotally connected at 42 and 43 to a side plate 45 of the middle bed section which is pivoted at 46 on the cross member 18 of the sofa bed support. The 55 pivots 42 and 43 are offset from each other in such a manner that when the back member 20 of the sofa is swung into its back supporting position on the sofa bed, as shown in Fig. 1, these two links or bars will be approximately side by side. It will also be noted that one end 60 of the spring 24 is connected to its fastening member 25 above the pivots 42 and 43 of the links 40 and 41, Fig. 2, and the other end of the spring, through the medium of the link 22 is connected with the back 20 below the pivots 38 and 39 of these links. Consequently the spring will

65 exert a pull on the back 20 tending to lift it or to counteract at least partly the weight of the back, thus facilitating

the swinging of the same into its upper position as shown in Fig. 2. When in this position, the spring has been shortened thus reducing the pull of the same on the back 20 and thus avoiding continued pull on the back which might cause it to swing with force against the person moving the back into its upper position. The link 41, as may be seen in Fig. 5, forms a part of the frame of a spring section of the bed which will hereafter be referred to as the first mattress supporting frame, and when in sofa position this frame part forms the support for a sofa seat cushion (not shown).

The pivots 42 and 43, which connect the links 40 and 41 with a side plate 45 of a mattress supporting section which will hereinafter also be referred to as the second mattress supporting section, are so spaced relatively to the pivots which connect these links with the leg member 27, that when the sofa back 20 is moved from its lower position in which it forms the back of the sofa seat into the upper position, as shown in Fig. 2, it will be approximately in the same angular relation to the support of the sofa bed. In other words, links 40 and 41 act somewhat like the opposite sides of a parallelogram. During this movement the spring 24 cooperating with the link 22 will, to a large extent, counter-balance the weight of the back 20 and parts connected therewith.

The side plate 45 of the middle bed section as shown is made up of angle bars 48, 49 and 51 which are suitably welded together. The pivot 43 connects the link 40 with the part 43 of the side plate 45 and the link 41, which forms a side frame of a bed section, is pivoted to the angle bar 49 of the side plate 45. When the parts have arrived in the position shown in Fig. 2, it will be noted that the link 40 adjacent to its pivot 43 abuts against the angle bar 49 so that no further swinging of the link 40 relative to the side plate 45 is possible. When the parts of the bed are pulled farther away from the support of the sofa bed i. e. beyond their upright positions shown in Fig. 2, the side plate 45 will consequently be forced to swing about its pivot 46, through approximately a right angle whereupon the parts thus far described assume the positions shown in Fig. 3. When this occurs the leg member 27 will rest on the floor and the spring 24 has been extended so that during the downward swinging of the parts from the position shown in Fig. 2 to that shown in Fig. 3 the spring 24 is again stretched or tensioned, thus resisting to some extent the downward swing of these parts. However, when the spring is in the position shown in Fig. 3, the pull exerted by the same will be approximately in dead center relation to some of the pivots of the parts described so that there is no tendency on the part of the spring to swing the back 20 and the links 40 and 41 upwardly or into their sofa positions. The parts will, therefore, remain in their bed positions without any tendency to move out of the same unless positively actuated.

The part of the mattress supporting frame which remains in the sofa bed support when the parts are in their bed positions includes a frame member 55 which will hereinafter also be referred to as the third mattress supporting frame member and which is pivotally connected at one end at 56 to the middle side plate 45 and at its other end by means of a pivot 57 to a leg member 58 which is of angle shape and has a link 60 pivoted thereto at 61. The other end of this link is pivoted at 62 to the part 43 of the side plate 45 of the middle bed section. When this side plate is in the position shown in Fig. 1, these parts will lie in the lower portion of the support of the sofa bed. When, however, the second mattress supporting side frame member 45 is swung about its pivot 46 from the position shown in Figs. 1 and 2 to that shown in Fig. 3, the link 60 and frame member 55 will assume the positions shown in Fig. 3 in which the supporting leg 58 takes an inclined position in which the lower end thereof rests upon the transverse bottom member 16 of the sofa bed support. When in this position

the mattress supporting member 55 will be in alignment with the mattress supporting member 41 and the angle bar 48 which supports the middle portion of the bed. This leg 58, by supporting the weight of a part of the bed on the member 16 of the support, holds the support down when a person sits on the middle portion of the bed and relieves the link 60 of the strain of supporting this part of the bed.

All three mattress supporting members have their side members 41, 45 and 55, connected by cross members 81, 82, 83 and 84. Also a back stop 14 projecting upwardly from cross member 84 prevents the mattress from sliding off the back edge.

The side plate 45 and one of its cross members 82 also has secured thereto a trim part 65 which forms a part of the lower front edge of the sofa when the parts are in the sofa position shown in Fig. 1. This trim part is movable with the side plate 45 so as to provide a place in the front cross member 18 for the pivot 46 sufficiently low to enable the bed to be at the usual distance above the floor.

When the parts are again replaced to their sofa positions, the sofa back 20 which forms one end of the bed, is raised back to the position shown in Fig. 2 in which the side plate 45 of the middle bed section swings about its pivot 46 because of the action thereon of links 40 and 41. This movement also restores the mattress supporting member 55 into its lower position in the support of the sofa bed, together with the link 60. This movement of the side plate 45 also causes the leg 58 to swing into a position substantially parallel with the frame member 55.

Upon a further push on the back 20 into a sofa position, the parts will move back into the position shown in Fig. 1 whereupon the latch 28 will swing by gravity into its locking position in engagement with the fixed part 33.

It will be noted that when the parts are in the bed position as shown in Fig. 3, the main frame or support of the sofa bed can be swung upwardly about the front end thereof into the position shown in Fig. 9, thus making it possible to sweep or otherwise clean the floor underneath the support of the sofa bed. This eliminates the necessity of shifting the sofa bed so as to render the floor underneath the support accessible.

When the rear end of the support is swung upwardly as shown in Fig. 9, it will be noted that the links 55 and 60 and the leg 58 will swing into their folded positions in the bottom portion of the support, similar to the positions which these parts occupy when the sofa bed is in the positions shown in Figs. 1 and 2.

The construction described is easily adaptable for actuation by power. When this is done the locking latch 28 is omitted and power actuated means are provided which are capable of exerting force on the link 41 which also constitutes a part of the frame of an intermediate section 55 of the mattress supporting spring frame of the bed. By the way of example, I have shown in Fig. 10 a hydraulic or pneumatic actuated piston 70 which cooperates with a cylinder 71. The cylinder may be pivoted at 72 at one end on the cross member 34 of the sofa bed support and the plunger or piston is pivoted at 73 on the link or frame member 41, adjacent to the side plate 45. When this mechanism is used the counter spring 24 and the link 22 may also be omitted. Fluid under pressure may be supplied to the opposite end of the cylinder by means of tubes or conduits 75 and 76.

It will be obvious upon examining the linkage and the fluid pressure operated power device that when the piston exerts pressure against the rod or frame member 41, this member will swing upwardly and also the middle bed section 45 will swing about its pivot 46 so that the parts of the sofa bed will be moved from the position shown in the full lines of Fig. 10 to the bed position indicated in broken lines in Fig. 10. When the force acting on the link 41 is reversed, for example by admitting fluid pressure through the tube 76, the reverse action will take

place so that the parts will be swung from their bed positions into the sofa positions.

I claim:

1. A sofa bed comprising a support having end members forming arm rests and connected by cross members, a mattress supporting frame disposed between said end members and including a plurality of frame parts hinged together, a member forming a back of the sofa when the parts of the sofa bed are in their sofa positions and which forms an end part of said mattress supporting frame when the parts of said sofa bed are in bed position, each side of said sofa bed having a pair of links pivotally connected to said back in spaced relation to each other, an intermediate mattress supporting frame part to which the other ends of said links are pivotally connected in spaced relation to each other, said sofa back being swingable upwardly on its connection with said links, and a spring having one end thereof connected above and forwardly of said last mentioned pivoted connections of said links and having the other end connected with said back below the pivot connections of said links with said back when said back is in sofa position, whereby said spring partly counterbalances the weight of said back until the same has been swung into a position above said support.

2. A sofa bed according to claim 1 in which a strip secured to said back and extending downwardly therefrom when said back is in sofa position is connected with the other end of said spring.

3. A sofa bed comprising a support having end members forming arm rests and connected by cross members, a mattress supporting frame disposed between said end members and including a plurality of frame parts hinged together, a member forming a back of the sofa when the parts of the sofa bed are in their sofa positions and which forms an end part of said mattress supporting frame when the parts of said sofa bed are in bed position, each side of said sofa bed having a pair of links pivotally connected to said back in spaced relation to each other, an intermediate mattress supporting frame part to which the other ends of said links are pivotally connected in spaced relation to each other, said intermediate mattress supporting frame part being pivoted intermediate of its ends on said support and having parts against which one of said links abuts when in its upright position and which causes said intermediate frame parts to swing about its pivotal connection with said support, a third mattress supporting frame part remaining permanently in said support and a link connecting said intermediate and said third frame parts to swing said third frame part into substantially horizontal alignment with other frame parts when said intermediate frame part is swung about its pivotal connection with said support.

4. A sofa bed according to claim 3 in which one of said links of each pair also constitutes the side of another mattress supporting frame part.

5. A sofa bed comprising a support having end members forming arm rests and connected by cross members, a mattress supporting frame disposed between said end members and including a plurality of frame parts hinged together, a member forming a back of the sofa when the parts of the sofa bed are in their sofa positions, leg members rigidly secured to opposite ends of said back and extending substantially horizontally when said back is

in upright position, a pair of links on each side of said sofa bed pivotally connected at one of their ends to said leg in spaced relation to each other, a second mattress supporting frame part to which the other ends of said links are pivotally connected in spaced relation to each other and which is pivotally mounted on said support, said sofa back being swingable upwardly on its connection with said links and then downwardly into bed position in which said legs rest on a floor, and parts on said links positioned to abut against parts of said second mattress supporting frame part when said links are swung on their pivotal connections with said support to push said second frame part to swing about its pivotal connection with said support into horizontal position during the downward swing of said back into bed position.

6. A sofa bed comprising a support having end members forming arm rests and connected by cross members, a mattress supporting frame disposed between said end members and including a plurality of frame parts hinged together, a member forming a back of the sofa when the parts of the sofa bed are in their sofa positions, leg members rigidly secured to opposite ends of said back and extending substantially horizontally when said back is in upright position, a pair of links on each side of said sofa bed pivotally connected to said leg in spaced relation to each other, a second mattress supporting frame part to which the other ends of said links are pivotally connected in spaced relation to each other and which is pivotally mounted on said support, said sofa back being swingable upwardly on its connection with said links and then downwardly into bed position in which said legs rest on a floor, cooperating parts on said links and said second mattress supporting frame part which abut after said back has been swung approximately half way into its bed position to swing said second frame part about its pivotal connection with said support during the downward swing of said back, a third mattress supporting frame part arranged in said support and having one end thereof pivoted to said second mattress frame, supporting legs pivoted on the other end of said third mattress supporting frame part, and another set of links connecting said second mattress supporting frame part with said pivoted legs for swinging the same for raising said third mattress supporting frame part to the level of the other mattress supporting frame parts when said second mattress supporting frame is swung on its pivotal connection with said support by said first mentioned pair of links.

7. A sofa bed according to claim 6 and including rollers for the lower ends of said last mentioned legs and a part on said support of said sofa bed on which said rollers roll when said last mentioned legs are swung on their pivots.
